DESIGN FOR A COMBINED HANDLE AND FRONT DRAWER PANEL

Herman E. De Vries, New York, N. Y., assignor to
H. T. Cushman Mfg. Co., North Benning-
ton, Vt.

Application November 11, 1935, Serial No. 59,480

Term of patent 3½ years

To all whom it may concern:

Be it known that I, Herman E. De Vries, a citizen of the United States, residing at New York city, in the county and State of New York, have invented a new, original, and ornamental Design for a Combined Handle and Front Drawer Panel, of which the following is a specification, reference being had to the accompanying drawing, forming part thereof.

Figure 1 is an elevation of a combined handle

and front drawer panel showing my new design;

Figure 2 is a cross-sectional view thereof, taken on line 2—2 of Figure 1; and

Figure 3 is a vertical sectional view taken on line 3—3 of Figure 1.

I claim:

The ornamental design for a combined handle and front drawer panel substantially as shown.

HERMAN E. DE VRIES.
